ARC LAMP

Garnet Philip Ham, Old Greenwich, Conn., assignor to American Cyanamid Company, New York, N. Y., a corporation of Maine

Application September 17, 1940, Serial No. 357,099

2 Claims. (Cl. 176—113)

This invention relates to arc lamps and more particularly to an improvement in high intensity carbon arc lamps used in blueprinting.

In operating the ordinary arc lamps which consist of a glass or quartz vessel containing two carbon electrodes separated by an air gap with current being supplied to the electrodes, unburned carbon and metal salts are ejected from the electrodes and are deposited on the walls of the vessel either by physical contact or by sublimation, gradually forming an opaque film. This problem is particularly acute in the case of high-intensity lamps so that if the arc is to be used over long periods of time with full efficiency, the glass chimney must be cleaned from time to time. This is not only troublesome but costly in the case of lamps which are used in blueprinting machines containing five or six automatic arc lamps for it interrupts the regular routine. On the other hand, if the carbon and sublimed metal salt deposits are allowed to collect on the walls of the vessel, the light intensity of the lamp diminishes rapidly to such an extent that in some cases blue prints show a decreased blue intensity for the same amount of exposure after only four hours operating time of the machine. In commercial practice the globes are cleaned after each day's run with soap and a medium abrasive powder but often this is not sufficient for the inner portions of the globe may show indications of molten areas which occlude carbon particles and inorganic salts. Hence such a glass is permanently impaired and cannot transmit its maximum illumination.

The present invention is directed to an improvement in arc lamps of the carbon electrode type which consists in directly removing from the area of the arc any unburned carbon particles and metal salts contained in the electrodes before they are disseminated or carried upward by convection currents within the globe and deposited on the walls of the glass container. The manner in which this is accomplished can be more readily understood by reference to the drawing in which:

Fig. 1 is a front plan view of an arc lamp of the present invention;

Fig. 2 is a sectional view showing in greater detail the means for exhausting unconsumed particles and combustion gases from the arc; and

Fig. 3 is a sectional view showing an alternative exhausting means.

Referring more specifically to the drawing, in Figs. 1 and 2 an open ended vessel 1 of transparent material such as glass or quartz is equipped with suitable closure means 2 and 3.

A carbon electrode 4 is passed down through the upper plate 2 and electrode support 11, properly insulated therefrom by means of bushing 6, and similarly plate 3 bears carbon electrode 5 which extends upward in the globe in direct line with carbon electrode 4, an arc gap of appropriate width being maintained between the two electrodes by any suitable adjusting mechanism (not shown). Current is supplied to the electrodes by any suitable means (not shown). A hollow tube 7 provided with a valve 8 is inserted through plate 2 and extends downward in the vessel until its lower end is adjacent to and in horizontal alignment with the tip of the upper positive electrode. The lower orifice 9 of the tube is preferably cupped and flared so that when suction is applied from without, the combustion gases, together with any unconsumed particles, are withdrawn from the upper region of the arc. Control is effected through valve 8 so that enough suction is applied to aspirate from the arc substantially all of the metal salts and carbon particles which might otherwise be dispersed and form a film on the walls of the vessel, without substantial distortion of the arc from its normal position between the electrodes. The preferred location and horn-shaped construction of the lower opening of the tube is shown in greater detail in Fig. 2.

In Fig. 3 a modified form of exhausting means to be applied to arc lamps is shown which consists of a tube 10 inserted into the lamp through plate 2, the lower open portion of which is flared to completely surround and enclose the lower portion of the positive electrode directly above the arc. The other parts of the lamp shown in this section correspond and bear the same reference numerals as those given in Figs. 1 and 2. The funnel-shape construction of the tube shown in this figure causes a circularly uniform withdrawal of exhaust gases, unburned carbon and inorganic matter ejected during operation of the lamp without veering the arc and interfering with light transmission. This is of special importance in lamps which are not equipped with magnetic deflectors such as are commonly employed on the outside of the globe running parallel to the arc flame. With this latter device a wavering or distortion of the flame can be corrected by a careful adjustment of the deflectors and the arc is then confined between the electrodes.

When the lamp is in operation small quantities of air can seep in between the upper electrode and its bushing as well as at the bottom, preferably to convert the products of combustion

substantially to carbon monoxide. The flow of gases bearing any non-gaseous particles ejected from the electrodes, follows the path of the arc from the negative to the positive electrode, a portion being reflected off the tip of the upper electrode and the remainder rushing past. Suction is applied to the exhaust tube placed adjacent to the tip of this upper electrode, or to the funnel as the case may be, and these gases containing any substances that cause fogging are sucked out and thus are prevented from ever reaching the glass walls.

The suction or reduction of pressure within the exit tube effecting exhaustion, is accomplished in any manner such as attaching to the end of the tube exterior to the lamp a low-powered pump or similar device which creates a partial vacuum within the tube. If the lamp is to be used in a blueprinting machine such as that described in U. S. Patent 1,988,593, a constant suction is maintained by means of a fan blower installed to cool the several arc lamps operating therein. The rush of air from the fan horizontally across the exterior open end of the inserted tubes is sufficient to cause a partial vacuum within the tubes; exhaust gases bearing unconsumed particles flow toward this low-pressure region, and thus film-forming substances are continually swept out of the lamp interiors. In other words, the fan blower of the machine is utilized in conjunction with arc lamps of the present invention not only to cool the glass or quartz globe which is necessary when the lamps are operating at high intensities over long periods of time, but also to exhaust combustion gases together with non-gaseous substances which otherwise would be deposited and form an opaque film on the walls of the vessel. As has been pointed out above, this is of prime importance in commercial blueprinting processes as it dispenses with periodic cleaning of the individual lamps in the machine and permits continuous operation as well as prolonging the life of the arc lamp. While, therefore, any standard pumping mechanism may be used, employment of the fan blower to effect pressure reduc-

tion is economically preferred when arc lamps of the present invention are used in large-scale blueprinting machines.

The tube or funnel for withdrawing the film-forming particles from the arc flame may be made of quartz, stainless steel, or any other suitable material. If stainless steel or other metal is used an insulating bushing should be provided. However, it is not intended to limit the present invention to any particular materials of construction nor to the structural details shown in the accompanying drawing and described above, as it may be desirable to employ various modifications depending on the particular design and use of the arc lamp or lamps if a plurality are employed, for example in a blueprinting unit.

While the present invention is directed to an improvement in arc lamps generally it is particularly important in arc lamps employing "core" electrodes where fogging is especially critical, and the term "carbon electrode" used in the specification and claims is therefore to be construed broadly as including core electrodes containing other substituents in addition to carbon.

What I claim is:

1. In an enclosed arc lamp of the blueprint printing type the improvement which comprises in combination a hollow exhaust tube one end of which is positioned adjacent the arc flame, the other opening being outside the lamp enclosure, means co-acting with said exterior opening for causing reduction of pressure within said exhaust tube, the size of the exhaust tube and the capacity of the co-acting means being such that in normal operation of the lamp there is no substantial wavering of the flame.

2. An improved arc lamp according to claim 1 in which one end of the hollow exhaust tube is flared to completely encircle the lower portion of the upper electrode directly above the arc flame, said flared end being provided with a flanged opening forming a sleeve through which the electrode passes.

GARNET PHILIP HAM.
